UNITED STATES PATENT OFFICE.

DANIEL KOPS, OF NEW YORK, N. Y.

CORSET.

SPECIFICATION forming part of Letters Patent No. 712,312, dated October 28, 1902.

Application filed May 26, 1902. Serial No. 108,911. (No model.)

To all whom it may concern:

Be it known that I, DANIEL KOPS, a citizen of the United States, residing at the borough of Manhattan, in the city, county, and State 5 of New York, have invented an Improvement in Corsets, of which the following is a specification.

My invention relates to apparel-corsets, with the object of providing a corset adapted to 10 impart or assist in imparting to the figure of the wearer the straight-front effect with an acceptable fullness over and back of the hips.

I provide a fabric body of peculiar form, where the respective halves of the corset are 15 alike, but reversed, and in which the fabric body is composed in the front and under-arm portions of a series of curved diagonal overlying strengthening-pieces that are graded and tapering and some of which run from 20 the lower front part of the corset around over the hips to the upper back part to draw upon the front at the back around the waist, so as to produce the straight-front effect by a tension or pull taken up and supported by the 25 back. In the hip portion of the corset I form the fabric body over and back of the hips of a series of pieces so connected as to form plaits adapted under the tension of use to open out and in so doing to provide a full- 30 ness of curved form.

In the drawings, Figure 1 is a diagrammatic elevation of one-half of the corset of my improved form. Fig. 2 is a cross-section at xx of Fig. 1. Fig. 3 represents, approximately, 35 the segregated pieces of which one-half of the corset is composed; and Fig. 4 is a cross-section representing a modification.

The series of curved diagonal overlying strengthening-pieces composing the fabric 40 body in the front and under-arm portions are represented at a , b , c , d , and e .

The portion a , which is the main portion, runs from the lower front portion of the corset around over the hips and increases in 45 width and forms the main back portion of the corset above the hips, a part of said portion extending up the front and embracing the front steels. There is thus a curved diagonal piece running from the back lacing-strip o 50 entirely around the side and down to the lower front portion of the corset, with an integral part extending up the front of the corset, and,

as hereinbefore stated, forming a part to which the front steels are connected.

The portion b is of substantially V shape 55 and fits in between the upper divided edges of the portion a , underlies the edges thereof, and is secured thereto by the lines of sewing 2. The breast gore-piece c fits within the upper divided portion of the piece b , underlies 60 the same, and is secured thereto by the lines of sewing 3, the corset assuming shape as the respective parts are sewed together.

The portion d of the fabric body coming at the front of the corset is in the form of an inverted V, with one portion underlying the portion a and connected thereto by lines of sewing 4, and a part of this portion d extends from the portion a down to the lower edge of the corset approximately at the forward portion of the hip, and the same is 70 joined to the series of pieces connected together and which extend over and back of the hips.

The gore-piece e comes at the front of the 75 corset, underlies the lower divided edges of the portion d , and is secured thereto by lines of sewing 5, the lower edge of the gore-piece e forming part of the lower edge of the corset. The portion e ties together the parts of 80 the portion d , and the portion d at the front of the corset substantially continues the line of the portion a which comes down from the back over the hips.

The hip portion of the corset, or, in other 85 words, the part of the fabric body that extends over and back of the hips, is composed of the sections f , g , h , i , k , l , m , and n in the order given, the sections f , h , k , and m forming the plait-pieces underlying the pieces d , 90 g , i , l , and n and connected to said pieces by the lines of sewing 6, 7, 8, 9, 10, 11, 12, and 13. The rearward edge of the portion d and the respective opposite edges of the portions g , i , l , and n are so connected to the plait-pieces f , h , k , and m that said parts come together at the lower edge of the corset and at the waist-line and diverge or taper in both directions from those points toward the line xx , upon which the section Fig. 2 is taken, 100 and the parts f , h , k , and m are preferably made with a center fold or crease, which when the corset is not in use upon the person of the wearer permits the edges of the parts d ,

g, i, l, and n to substantially come together and lie edge to edge; but when the corset is in use upon the figure of the wearer these plait-pieces open out, so as to create in this 5 part of the corset an outwardly-curved or convex form from the waist to the lower edge, so as to thereby cause an acceptable fullness over and back of the hips, causing the corset to conform closely to the figure of the wearer. 10 This close conforming and fitting of this part of the corset has a steady tendency with reference to the front portion of the corset, preventing the front portion of the corset moving out with any tendency to fullness in 15 the figure and, further, causing the corset to have the function of confining the figure and imparting thereto the flat form at present so acceptable.

I do not limit myself to the exact shape of 20 the parts a to o, inclusive, as shown in Fig. 3, because slight modifications of the shape may be required in corsets of different sizes, the general outline being in all cases substantially maintained, and I do not limit myself 25 to the precise shape of the plait-pieces f, h, k, and m, as they may be made wider at the central portion, so that the plaits are fuller and increase the fullness over and back of the hips, and I may in these plait portions 30 employ bones, as shown at r, Fig. 1, for the purpose of stiffening the said parts in which otherwise there would be no bones or bone-pockets. I have not shown in Fig. 1 any of the 35 bone-pockets or bones employed as stiffeners in the corset, but only the series of parts going to make up the fabric body of the corset and their manner of connection. According to my invention I propose placing all of the bone-pockets and bones required as stiffeners 40 upon the inner surface of the corset, strips being sewed thereto to receive the bones upon the under surface, mainly for the reason that in the present style of fitting garments a smooth exterior to the corset is required, and 45 in order to obtain this it is necessary to put the bone-pockets and bones upon the under surface of the corset.

In Fig. 2 by the cross-section at the line xx I have not only illustrated the point of greatest 50 fullness over and back of the hips and have represented the manner of connecting the various sections forming this part of the corset together with the plaits, but have shown the bone-pockets s as secured to the under surface of the various parts connected to form the fabric body.

The bone-pockets and bones employed in the corset of my present invention not only extend from approximately the upper to the 60 lower edges of the corset and are secured, as hereinbefore stated, upon the under surface of the fabric body, but where said bone-pockets and bones come in the part of the corset lying over and back of the hips I prefer to 65 arrange the said bone-pockets and bones, so that they follow along the respective opposite edges of the plaits, so as to positively

stiffen and hold the respective parts g, i, l, and n at their respective opposite edges.

The modification shown in Fig. 4 has special reference to the parts extending over and back of the hips, and the same shows a modified form of plait h' between the sections g' and i', in which instead of the plait being flexible it is made rigidly tapering from the 70 respective ends to the center, and bone-pocket and bone therein are secured to the under or back of the fabric body, so that the plait is maintained in a fixed and distended position. 75

I may find it advantageous to make some 80 of the plaits flexible, some flexible with short bone-pockets and bones r, to make some of the plaits of the form shown in the modification, Fig. 4, or to alternate the forms of construction, so that in the one corset there are 85 both flexible and rigid plait portions.

I claim as my invention—

1. A corset comprising a series of curved, diagonal, overlying, strengthening-pieces in the front and under-arm portions, a part of 90 which run from the lower front portion of the corset around over the hips and into the back portion of the corset above the hips, and a series of main and intermediate plait portions connected therewith and extending over 95 and back of the hips, substantially as set forth.

2. A corset in which the fabric body in the front and under-arm portions consists of curved diagonal, overlying strengthening-pieces running in part from the lower front 100 portion of the corset around over the hips and into the back of the corset, and a series of connected curved portions extending over and back of the hips and connected with the front and under-arm portions, and adapted 105 to impart a fullness to this part of the corset, substantially as set forth.

3. In a corset, a series of curved, diagonal, overlying pieces composing the fabric body in the front and under-arm portions of the 110 corset, that are graded and tapering and some of which run from the lower front portion of the corset around over the hips to the upper back part and have the function of drawing upon the front at the back around the waist 115 so as to hold down the front portion of the corset, substantially as set forth.

4. In a corset, the combination with a series of curved, diagonal sections forming the fabric body in the front and under-arm portions, of a series of pieces of material forming the fabric body of curved form, and intermediate plait-pieces connected together and extending over and back of the hips and having an extensible function to produce a 125 fullness at this point, substantially as set forth.

5. A corset having in the fabric body-sections a main section a running from the lower front portion of the corset around over the hips and increasing in width and forming the 130 main back portion of the corset above the hips, and having a part thereof extending up the front and embracing the front steels, substantially as set forth.

6. A corset having in the fabric body-sections, a main section *a* running from the lower front portion of the corset around over the hips and increasing in width and forming the main back portion of the corset above the hips and having a part thereof extending up the front and embracing the front steels, and a portion *b* of substantially V shape and fitting in between the upper divided edges of the portion *a*, underlying the edges thereof and connected thereto by lines of sewing, and a breast gore-piece *c* fitting within the upper divided portion of the piece *b*, underlying the same and secured thereto by lines of sewing, substantially as set forth.
7. A corset having in the fabric body-sections a main section *a* running from the lower front portion of the corset around over the hips and increasing in width and forming the main back portion of the corset above the hips and having a part thereof extending up the front and embracing the front steels, and a portion *b* of substantially V shape and fitting in between the upper divided edges of the portion *a*, underlying the edges thereof and connected thereto by lines of sewing, and a breast gore-piece *c* fitting within the upper divided portion of the piece *b*, underlying the same and secured thereto by lines of sewing, and a portion *d* of substantially inverted-V form and underlying and connected to part of the lower edge of the portion *a* by lines of sewing, and a gore-piece *e* fitting within the divided upper edges of the portion *d*, underlying the same and connected thereto by lines of sewing, substantially as set forth.
8. In a corset, and in combination with a series of curved, diagonal, overlying pieces composing the fabric body in the front and under-arm portions, of the fabric body-sections *g*, *i*, *l* and *n* and the intermediate plait-sections *f*, *h*, *k* and *m* secured thereto and at one edge to the aforesaid fabric body-sections and extending over and back of the hips and connected in such a manner that the respective edges along the waist and lower edges of the corset substantially meet and are spread apart by the plaits at the central line, substantially as set forth.
9. In a corset, and in combination with a series of curved, diagonal, overlying pieces composing the fabric body in the front and

under-arm portions, of a series of pieces of material forming the fabric body of curved form, and intermediate plait-pieces connected together and extending over and back of the hips and having an extensible function to produce a fullness at this point, and one or more bone-pockets and bones therein extending along the center line of one or more of said plats and secured to the surface of the material of the fabric body, substantially as set forth.

10. In a corset, and in combination with a series of curved, diagonal, overlying pieces composing the fabric body in the front and under-arm portions, of a series of pieces of material forming the fabric body of curved form, and intermediate plait-pieces connected together and extending over and back of the hips and having an extensible function to produce a fullness at this point, and a series of bone-pockets and bones therein secured to the under surface of the fabric body of the corset and extending approximately from the upper to the lower edges of the corset, and where said parts extend over and back of the hips, placing said bone-pockets and bones along the respective edges of the plait-pieces, substantially as and for the purposes set forth.

11. In a corset, and in combination with a series of curved, overlying pieces composing the fabric body in the front and under-arm portions and also in the portion extending over and back of the hips and between which are series of plait portions providing for an extensible function to produce a fullness in the corset, of a series of bone-pockets and bones therein secured to the under surface of the fabric body of the corset and extending approximately from the upper to the lower edges of the corset, and where said bone-pockets and bones come into proximity to the plait portions placing said bone-pockets and bones along the respective edges of the plait-pieces, substantially as and for the purposes set forth.

Signed by me this 23d day of May, 1902.

DANIEL KOPS.
